UNITED STATES PATENT OFFICE

JOHN GIGLIO, OF NEW YORK, N. Y.

WINDOW CONSTRUCTION

Application filed September 19, 1929. Serial No. 393,760.

This invention relates to improvements in window constructions of the type having a sliding stile and provided with a vertically hinged sash.

5 The primary object of this invention, is to provide a device of the above mentioned character, having novel means of locking the sliding stiles against vertical movement whereby the sliding stiles may be locked 10 from the inside of the building to prevent the admittance of unauthorized persons.

A still further object of this invention, is to provide a window construction of the 15 above character having a novel form of locking means for locking the hinged sashes in their closed position comprising screw threaded rods passing therethrough and entering screw threaded bushings in the sliding stiles.

20 A still further object of this invention, is to provide a window construction of the above mentioned character having vertically hinged sashes whereby the same may be opened inwardly for the purpose of easily 25 cleaning the transparent panes by washing or the like.

Other objects and advantages of the invention will become apparent during the course of the following description, forming 30 a part of this specification and wherein like reference characters are employed to designate like parts throughout the same wherein in the drawings is shown in Figure 1 a plan view of the window construction illustrating the arrangement of the vertically pivoted sash frames relative to the vertically sliding stiles.

Figure 2 is a fragmentary cross sectional view on lines 2-2 of Figure 1 showing the 35 sash frames in their locked position.

Figure 3 is a cross sectional view showing the free ends of the vertically pivoted sash frame presented to the sliding stiles.

Figure 4 is a fragmentary side elevational 40 view of the sliding stile showing the hinged joint of the vertically pivoted sash frames.

Figure 5 is a fragmentary view showing 45 one of the vertically sliding stiles in rear elevation and the vertically pivoted sash 50 frame in perspective.

Figure 6 is a transverse cross sectional view showing the means for locking the vertically pivoted sash frames in their closed positions.

Figure 7 is a transverse cross sectional 55 view of the invention showing the vertically pivoted sash frames in their open position, and Figure 8 is a vertical cross sectional view taken on lines 8-8 of Figure 7 looking in the direction of the arrows and showing 60 the vertically pivoted sash frames and the hinges therefor secured to the vertically sliding stiles.

In the drawings wherein is shown a preferred embodiment of the invention and 65 wherein for the purpose of more clearly illustrating the invention in detail, the reference character A will generally be employed to designate the wall of a building or the like having an opening for receiving a rectangular hollow metal window frame 10 having lateral flanges 11 and 12 on the opposite sides thereof. The rectangular metal frame pieces 10 are held in place by ornamental wainscoating 13 and 14 secured to the wall A 70 on opposite sides of the rectangular metal frame pieces 10.

Slidably mounted on opposite sides of the lateral flange 12 is a pair of sliding stiles 14 and 15 which are adapted to slide between 80 the wainscoating 13 and 14 and the lateral flange 12, as best illustrated in Figures 6 and 7. Hingedly secured to the sliding stiles 15 is a vertically pivoted window frame 16 by means of suitable hinges 17. One of the 85 hinges 17 may be of the multiple pintle type in order that the inner swinging sash 16 may swing to a position shown in Figure 7 out of the path of the outer swinging window sash 16. Each of the vertically pivoted sash 90 frames 16 are provided with transparent panes 18 and are held in place in the usual manner.

The sliding stiles 14 are provided with transverse openings 19 adapted to receive 95 screw threaded bushings 20 which may be anchored in place well known in this type of screw threaded hold. Corresponding lateral openings 20 and 21 in the vertically pivoted sash frames 16 are adapted to receive 100

locking bolts 22 having screw threaded ends 23 at one end adapted to be received in the screw threaded bushings 20 of the sliding stiles 14, whereby the vertically pivoted sash frames may be held in a locked position relative to the sliding stiles 14 and 15.

Locking pins 30 are adapted to pass through the vertically sliding stiles 14 and through the lateral flanges 12 as more clearly shown in Figure 3, to hold the sash frames and the sliding stiles against vertical movement. The usual type of window fastener 31 is provided on the vertically pivoted sash frames 16 for holding the same against further vertical sliding movement.

It is to be understood that the form of invention herewith shown and described is to be taken as a preferred example of the same and that various changes in the shape, size and arrangement of parts may be resorted to without departing from the spirit of the invention and the scope of the subjoining claim.

What I claim is:—

25 A window construction of the character described, comprising pairs of slidably mounted stiles, the stiles of each pair being arranged at inner and outer sides, respectively, of the window construction, the outer 30 stile of each pair being of a width greater than the width of the inner stile, a vertically hinged sash frame attached to the inner edge of each stile of one pair, and adapted to be swung laterally, the inner sash frame being 35 double hinged on multiple pintles and adapted to be swung out of the path of the outer sash frame, and into engagement with the window frame to occupy a position at right angles to the plane of the window opening 40 and the outer sash being limited in its opening movement by abutting contact with the inner stile to occupy a position parallel with the opened inner sash, and means for detachably securing the other sides of the 45 sashes to the respective stiles at the other side of the window construction.

In testimony whereof I affix my signature.
JOHN GIGLIO.
